(57) **CLAIM**

The ornamental design for a vehicle park lamp, as shown and described.

DESCRIPTION

FIG. 1 is a left side elevational view of a left vehicle park lamp (the right vehicle park lamp being a mirror image and is not shown);

FIG. 2 is a right side elevational view of the vehicle park lamp;

FIG. 3 is a front elevational view of the vehicle park lamp;

FIG. 4 is a top plan view of the vehicle park lamp;

FIG. 5 is a bottom plan view of the vehicle park lamp;

FIG. 6 is a perspective view of the vehicle park lamp; and,

FIG. 7 is another perspective view of the vehicle park lamp.
